UNITED STATES PATENT OFFICE.

JOHN RIJKONEN, OF CHICAGO, ILLINOIS.

PAINTER'S EXTENSION-PLANK.

968,805.

Specification of Letters Patent. Patented Aug. 30, 1910.

Application filed January 16, 1909. Serial No. 472,745.

To all whom it may concern:

Be it known that I, JOHN RIJKONEN, a subject of the Czar of Russia, residing at Chicago, in the county of Cook and State of Illinois, have invented a new and useful Improvement in Painters' Extension-Planks, of which the following is a specification.

My invention relates to that class of supports called "planks" used by painters, paper hangers and decorators in the interior of buildings in which the rooms, halls, etc., vary in floor space and various lengths of planks are required for the support of the workmen in the performance of their work on the upper parts of the walls and ceilings.

The object of my invention is to provide a plank having independent slideable extensions; a main body supporting the extensions which consists of two portions pivotally joined together and adapted thereby to be folded close together and secured for easy transportation under the arm; which when opened for use will lock automatically in the open position; the locking mechanism forming a truss by which the plank is adapted to sustain a weight several times greater than is ever required to be placed upon it, thereby providing for the lightest construction and material and thus providing for the lightest, longest, strongest, most adjustable and convenient for use and transportation.

The manner in which I accomplish my object is described in the following specification and illustrated in the accompanying drawings in which:

Figure 1 is a top plan of the device when folded for use, transportation or storage. Fig. 2 is a side elevation of the device folded as shown in Fig. 1. Fig. 3 is a left end elevation and Fig. 4 a right end elevation of the device in the positions as shown in Figs. 1 and 2. Fig. 5 is a top plan of the device opened out to the locked position of the two main parts. Fig. 6 is a side elevation, the parts being in the same position as in Fig. 5 resting on the top of supporting ladders, the dotted lines indicating the extensions and change in position of the supporting ladders. Fig. 7 is an enlarged detail of the locking mechanism. Fig. 8 is an enlarged detail of Fig. 7. Fig. 9 is an enlarged detail of part of the lock shown in Fig. 7. Fig. 10 is an underneath plan of the parts in the position shown in Fig. 5. Fig. 11 is the same as Fig. 10 with the extension partly drawn out. Fig. 12 is a vertical cross sec-

tion on the line 12—12 Fig. 11. Fig. 13 is a detail side view of the lock, the parts being in the position shown in Figs. 10 and 11. Fig. 14 is a detail side view of the parts shown in Fig. 13 in the position shown in Fig. 3.

In the drawings A indicates the left part and A¹ the right part of the main body of the device. Each of these parts consist of a main center bar B and B¹ and smaller bars B². At the pivoted ends of these parts the bars B² are spaced from each other by space blocks B³, and secured together by the tie rods B⁴. At the other ends the bars B, B¹, and B² are spaced and tied together by tie plates B⁵ and bolts B⁶. Slidably supported between the bars and tie plates of the parts A and A¹ are extensions C and C¹. These parts consist of bars C². The ends of the bars slidable in the parts A and A¹ are secured together by the tie plates C³ and bolts C⁴. The exterior ends are spaced by the blocks C⁵ and secured together by the tie rods C⁶. Secured to the underside of the bars B² and blocks B³ are hinge plates D, these together with the brackets D¹ are pivotally joined by the bolts D². Pivotedly connected to the brackets D¹ are truss rods D³. The other ends D⁴ of these rods are adapted to be parts of a locking device herein after described.

Secured to the undersides of the center bars B and B¹ are slotted lock plates E. These plates are adapted to guide and slidably secure the ends D⁴ of the truss rods, the movements of which are limited by the slots E¹. On the side of these lock plates, secured on the bars B and B¹ are spring latches F. Under the free end of each of these latches, the ends D⁴ of the truss rods are moved and are locked when the parts A and A¹ are opened to the position shown in Fig. 6. To release the truss rods from this locked position, the latches are moved by pressure on the ears F¹, till the ends D⁴ of the truss rods are free. When the parts A and A¹ are folded together the ends D⁴ of the truss rods slide to the other end of the lock plates as shown in Fig. 2. To hold the parts A and A¹ in the folded position the hooks G in the ends of the extensions C and C¹ are made fast as shown in Figs. 2 and 4.

When the several parts are constructed and combined as described and illustrated the device is operated and used as follows:

For storage, transportation or use in the smallest space, the parts A and A¹ are folded and hooked together in the position shown in Figs. 1, 2, 3, and 4. When in general use 5 the parts A and A¹ are opened to the position shown in Figs. 5 and 10. As these parts are opened the ends D⁴ of the truss rods D³ slide from the position shown in Fig. 14 along the plates E and under the nose F² of 10 the latch F. When the end D⁴ reaches the end of the slot the latch snaps over it as shown in Fig. 13. When both ends reach the locked position the brackets D¹ are vertical 15 as shown in Fig. 6, and the truss complete and secure. When a greater length is required one or both extensions can be drawn out as shown in Fig. 11, the horses or ladders being moved to the extensions as shown by the dotted lines in Fig. 6.

20 What I claim and desire to secure by Letters Patent is:—

A device of the kind described, consisting of two main portions constructed of a series 25 of bars slidably connected together, two pairs of angle plates secured to the underside of the fixed outer bars, the vertical parts of each pair of plates being adapted to be joined by a pivot bolt and thereby form hinged joints connecting said main portions; a pair 30 of plate bar brackets bent in the form of a V the ends thereof being twisted and thereby

adapted to form a pivot joint at the apex and to be pivotally joined at the other ends to said angle plates and thereby form part of said hinge joints; pivot bolts and nuts 35 adapted for joining said parts; two longitudinal bars pivotally connected to the apex joint of said brackets, the opposite ends of said bars bent at right angles and forming a horizontal transverse projection; a pair of 40 slotted plates secured one to the underside of the central fixed bar in each of said main portions and spaced therefrom, each of said plates being adapted to slidably secure the transverse projecting end of said longitudinal bars; and a pair of spring latches, 45 secured one on each of said central fixed bars parallel with said slotted plates the free end of each of said latches being adapted to be raised by said projecting ends of said bars 50 slidable in said plate and to snap lock said bars in said plates when said main portions are extended for use and to be raised and thereby release said bars whereby said bars are free to slide in said plates when said 55 main portions are folded together as described.

JOHN RIIKONEN.
